UNITED STATES PATENT OFFICE

149,134

DESIGN FOR A FLOOR BRUSH

Alfred L. Le Febvre, Windsor, Conn., assignor to
The Fuller Brush Company, Hartford, Conn.,
a corporation of Connecticut

Application June 7, 1946, Serial No. 130,497

Term of patent 14 years

(Cl. D9—2)

To all whom it may concern:

Be it known that I, Alfred L. Le Febvre, a citizen of the United States, residing at Windsor, in the county of Hartford and State of Connecticut, have invented a new, original, and ornamental Design for a Floor Brush, of which the following is a specification, reference being had to the accompanying drawing, forming part thereof.

The figure of the drawing is a perspective view of a floor brush incorporating my new design. The end and side of the brush not shown in the drawing are the same as the side and end shown.

I claim:

The ornamental design for a floor brush, as shown and described.

ALFRED L. LE FEBVRE.
